Des. 229,733

Patented Jan. 1, 1974

229,733

CHAFING DISH FOR FONDUE OR THE LIKE

Fred Press, White Plains, N.Y., assignor to House
Mates Inc., Hartsdale, N.Y.

Filed June 23, 1971, Ser. No. 156,166

Term of patent 14 years

Int. Cl. D7—02

U.S. Cl. D7—90

T1—1.

T1—2.

FIG. 1 is a side elevational view of a chafing dish for fondue or the like showing my new design;

FIG. 2 is a top plan view thereof;

FIG. 3 is a sectional view taken along line 3—3 of FIG. 1 with the bowl portion omitted for clarity of illustration; and

FIG. 4 is a sectional view taken along line 4—4 of FIG. 1.

I claim:

The ornamental design for a chafing dish for fondue or the like, substantially as shown and described.
